[57] ABSTRACT

The present invention relates to apparatus and method

of synthesizing speech for synthesis units which form words. The method comprises the steps of generating, for each of multiple utterances of a given synthesis unit, a series of frames of analysis data, the frames being generated one frame every T_0 period, each frame in each series having a parameter value associated therewith; where one series results in M frames of data, partitioning each other series of frames to provide M time intervals each of which corresponds to one of the frames of said one series; synthesizing speech data for the synthesis unit, the synthesized speech data corresponding to a sequence of time intervals wherein each time interval has an associated parameter value, said synthesizing step including the steps of:

(a) representing the synthesized data as a sequence of M time intervals, interpolating each i th time interval (where $1 \leq i \leq M$) for the synthesized data from the respective i th intervals corresponding to the utterance; and

(b) interpolating the parameter value at each i th time interval of the synthesized data from the parameter values for the respective i th intervals corresponding to the utterances.

**VARIABLE SPEED SPEECH SYNTHESIS BY
INTERPOLATION BETWEEN FAST AND SLOW
SPEECH DATA**

FIELD OF THE INVENTION

The present invention generally relates to speech synthesis and, more particularly, to a speech synthesis process and system wherein the durations of speeches may be varied conveniently with the quality of their phonetic characteristics maintained high.

PRIOR ART

The speaking speed or duration of natural speech may vary due to various factors. For example, the duration of a spoken sentence as a whole may be extended or reduced according to speaking tempo. Also, the durations of certain phrases and words may be locally extended or reduced according to linguistic constraints such as structures, meanings and contents, etc., of sentences. Further, the durations of syllables may be extended or reduced according to the number of syllables spoken in one breathing interval. Therefore, it is necessary to control the durations of speeches in order to obtain synthesized speech of high quality, namely similar to natural speech.

In the prior art, there have been proposed two techniques for controlling the duration of speech. In one of the techniques, synthesis parameters in certain portions are removed or repeated while, in the other, periods of synthesis frames are varied. (Periods of analysis frames are fixed). These techniques are described in Japanese Published Unexamined Patent Application No. 50-62,709, for example. The above-mentioned technique of removing and repeating synthesis parameters requires the finding of content vowel portions by inspection and setting them as variable portions beforehand, thus requiring complicated operations. Further, as the duration of a speech varies, the phonetic characteristics also change since the dynamic features of articulatory organs transform. For example, the formants of vowels are generally neutralized as the duration of a speech is reduced. In the first noted prior technique, it is impossible to reflect such changes in synthesized speeches.

In the other prior technique of varying the periods of synthesis frames, all the portions of a speech are extended or reduced uniformly. Since ordinary speeches comprise portions which are individually extended or reduced remarkably or slightly, such a prior technique would generate quite unnaturally synthesized speeches. Of course, this prior technique cannot reflect the above-stated changes of the phonetic characteristics in synthesized speeches.

SUMMARY OF THE INVENTION

As a consequence of the foregoing difficulties in the prior art, it is an object of the present invention to provide a speech synthesis process and system wherein the durations of synthesis units (e.g., phonemes, syllables, words, etc.) for speech synthesis may be varied conveniently with the quality of their phonetic characteristics being maintained high.

In order to accomplish the above object, in the present invention, a plurality of speeches extending over different durations obtained for a synthesis unit are analyzed, respectively, and a plurality of resultant analysis data are interpolated to be used for speech synthesis.

More specifically, a speech to be synthesized, extending over a target duration, comprises a plurality of variable period-length frames, each corresponding, one-to-one, to frames of a first set of basic analysis data (referring to as first data portions). Also, the frames of the first basic analysis data (the first data portions) and frames of a second basic analysis data (second data portions) are matched based on their acoustic characteristics. That is, each of the variable period-length frames of the speech to be synthesized is matched with a predetermined portion of the first basic analysis data (a first data portion) and a predetermined portion of the second basic analysis data (a second data portion). The period lengths of the variable period-length frames of the speech to be synthesized are determined by interpolating the period lengths of the corresponding portions of the first and second basic analysis data. The synthesis parameters of the variable period-length frames of the speech to be synthesized are determined by interpolating the synthesis parameters of the corresponding portions of the first and second basic analysis data.

Additional sets of analysis data may be employed to correct the period lengths and synthesis parameters of the variable period length frames of the speech to be synthesized.

Further, a synthesized speech of higher quality can be obtained by analyzing a speech spoken at a standard speed to obtain the origin for interpolation, which is either the first or second basic analysis data.

It is possible to match the first basic analysis data with the second basic analysis data with relatively few calculations by employing a dynamic programming.

BRIEF DESCRIPTION OF THE DRAWINGS

FIG. 1 shows a block diagram illustrating a system for executing a first embodiment of the present invention, as a whole.

FIG. 2 shows a flow chart for explaining the processing performed by the system in FIG. 1.

FIGS. 3 through 8 show diagrams for explaining the processing illustrated in FIG. 2.

FIG. 9 shows a block diagram illustrating another convenient system which may be replaced for the system in FIG. 1.

FIG. 10 shows a diagram for explaining a modification of the first embodiment.

FIG. 11 shows a flow chart for explaining the processing performed in the modification.

FIG. 12 shows a diagram illustrating another modification of the first embodiment.

**DESCRIPTION OF PREFERRED
EMBODIMENTS**

Referring now to the drawings, the present invention will be explained more in detail with reference to an embodiment thereof applied to the Japanese text-to-speech synthesis by rules. The text-to-speech synthesis performs an automatic speech synthesis from any input text and generally includes four stages of (1) inputting a text, (2) analyzing a sentence, (3) synthesizing a speech, and (4) outputting the speech. In stage (2), phonetic data and prosodic data are determined with reference to a Kanji-Kana conversion dictionary and a prosodic rule dictionary. In stage (3), synthesis parameters are sequentially read out with reference to a parameter file. In this embodiment, wherein one synthesized speech is generated from two input speeches, as will be stated

later, a composite parameter file is employed. This will be described later in more detail.

As synthesis units for speech synthesis, 101 Japanese syllables are used.

FIG. 1 illustrates a system for realizing an embodiment of the process of the present invention, as a whole. In FIG. 1, a workstation 1 for inputting a Japanese text can perform Japanese processings such as Kanji-Kana conversions. The workstation 1 is connected through a line 2 to a host computer 3 to which auxiliary storage 4 is connected. Most of the procedures in this embodiment, which can be realized with software executed by the host computer 3, are illustrated in blocks indicating the functions performed. The functions in these blocks are detailed in FIG. 2. In the blocks of FIGS. 1 and 2, like portions are illustrated with like numbers.

Further, to the host computer 3, a personal computer 6 is connected through a line 5. An A/D-D/A converter 7 is connected to the personal computer 6. To the converter 7, a microphone 8 and a speaker 9 are connected. The personal computer 6 executes routines for driving the A/D conversions and D/A conversions.

In the above configuration, when a speech is input into the microphone 8, the input speech is A/D converted, under the control of the personal computer 6, and then supplied to the host computer 3. A speech analysis function 10, 11 in the host computer 3 analysis digitized speech data for each of a plurality of analysis frame periods T_0 ; generates synthesis parameters; and stores them into the storage 4. This is shown with lines 1₁ and 1₂ in FIG. 3. With respect to the lines 1₁ and 1₂, the analysis frame periods are shown as T_0 and the synthesis parameters are shown as P_i and q_i . In this embodiment, line spectrum pair parameters are employed as synthesis parameters, although formant parameters, PARCOR coefficients, and so on may also be employed.

A parameter train for a speech to be synthesized is shown with a line 1₃ in FIG. 3. The period lengths T_1-T_m of M synthesis frames shown are variables and the synthesis parameters are shown as r_i . The parameter train will be explained later more in detail. The synthesis parameters of the parameter train are sequentially supplied to a speech synthesis function 17 in the host computer 3 and digital speech data representing the speech to be synthesized is supplied to the converter 7 through the personal computer 6. The converter 7 converts the digital speech data to analogue speech data under the control of the personal computer 6 to generate a synthesized speech through the speaker 9. FIG. 2 illustrates the steps of this embodiment as a whole. In FIG. 2, a parameter file is first established. Namely, a speech obtained by speaking one of the synthesis units (e.g. one of the 101 Japanese syllables) at a low speed is analyzed (Step 10). The resultant analysis data comprises M consecutive frames, each having the frame period T_0 , for example, as shown with the line 1₁ in FIG. 3. The duration t_0 of the analysis data for the synthesis unit is $(M \times T_0)$. Next, a speech obtained by speaking the same synthesis unit at a higher speed is analyzed (Step 11). The resultant analysis data comprises N consecutive frames, each having the frame period T_0 , for example, as shown with the line 1₂ in FIG. 3. The duration t_1 of the analysis data for the synthesis unit is $(N \times T_0)$. Then, the analysis data in the line 1₁ and 1₂ are matched by Dynamic Programming (DP) matching (Step 12).

As illustrated in FIG. 4, a path P which has the smallest cumulative distance between the frames is obtained by the DP matching, and the frames in the lines 1₁ and 1₂ are matched in accordance with the path P. In practice, the DP matching can move only in two directions, as illustrated in FIG. 5. Since one of the frames in the speech spoken at the lower speed should not correspond to more than one of the frames in the speech spoken at the higher speed, such a matching is prohibited by the rules illustrated in FIG. 5.

Thus, similar frames have been matched between the lines 1₁ and 1₂, as illustrated in FIG. 3. Namely, $p_1 \longleftrightarrow q_1, p_2 \longleftrightarrow q_2, p_3 \longleftrightarrow q_2 \dots$ have been matched as similar frames. A plurality of frames in the line 1₁ may correspond to one frame in the line 1₂. In such a case, the frame in the line 1₂ is equally divided into portions and each of said portions is deemed to correspond to each of said plurality of frames in the line 1₁. For example, in FIG. 3, the second frame and the third frame in the line 1₁ correspond to respective half portions of the second frame in the line 1₂. As a result, the M frames in the line 1₁ correspond to M period portions in the line 1₂, respectively. It is apparent that these period portions do not always have the same period lengths.

The speech to be synthesized, extending over a duration t between the durations t_0 and t_1 , is shown with the line 1₃ in FIG. 3. This speech to be synthesized comprises M frames, each corresponding to one frame in the line 1₁ and to one period portion in the line 1₂. Accordingly, each of the frames in the speech to be synthesized has a period length interpolated between the period length of the corresponding one frame in the line 1₁, i.e., T_0 , and the period length of the corresponding one period portion in the line 1₂. The synthesis parameters r_i of each of the frames are parameters interpolated between the corresponding synthesis parameters p_i and q_i .

After the DP matching, a period length variation ΔT_i and a parameter variation Δp_i of each of the frames are obtained (Step 13). The period length variation ΔT_i indicates a variation from the period length of the "i"th frame in the line 1₁, (i.e., T_0), to the period length of the period portion in the line 1₂ corresponding to the "6"th frame in the line 1₁. In FIG. 3, ΔT_2 is shown as an example thereof. When the frame in the line 1₂ corresponding to the "i"th frame in the line 1₁ is denoted as the "j"th frame in the line 1₂, ΔT_i may be expressed as

$$\Delta T_i = T_0 \frac{n_j - 1}{n_i}$$

where n_j denotes the number of frames in the line 1₁ corresponding to the "j"th frame in the line 1₂.

When the duration t of the speech to be synthesized is expressed by linear interpolation between t_0 and t_1 , with t_0 selected as the origin for interpolation, the following expression may be obtained.

$$t = t_0 + x (t_1 - t_0)$$

where $0 \leq x \leq 1$. The x in the above expression is herein-after referred to as an interpolation variable. As the interpolation variable approaches 0, the duration t approaches the origin for interpolation. Expressed in terms of the interpolation variable x and the variation ΔT_i , the period length T_i of each of the frames in the speech to be synthesized is interpolated as:

$$T_i = T_0 - x \Delta T_i$$

Where T_0 is a frame period selected as the origin for interpolation. Thus, by obtaining ΔT_i , the period length T_i of each of the frames in a speech to be synthesized, extending over any duration between t_i through t_0 can be obtained.

On the other hand, the parameter variation Δp_i is $(p_i - q_i)$ and the synthesis parameters r_i of each of the frames in the speech to be synthesized may be obtained by the following expression.

$$r_i = p_i - x \Delta p_i$$

Accordingly, by obtaining Δp_i , the synthesis parameters r_i of each of the frames in a speech to be synthesized, extending over any duration of length between t_1 through t_0 , can be obtained.

The variations ΔT_i and Δp_i thus obtained are stored into the auxiliary storage 4 together with p_i with a format such as illustrated in FIG. 7. The above processing is performed for each of the synthesis units for speech synthesis in order to form a composite parameter file.

With the parameter file formed, the text-to-speech synthesis is ready to be started, and a text is input (Step 14). The text is input at the work-station 1 and the text data is transferred to the host computer 3, as stated before. A sentence analysis function 15 in the host computer 3 performs Kanji-Kana conversions, determinations of prosodic parameters, and determinations of durations of synthesis units. This is illustrated in the following Table 1 showing the flow chart of the function and a specific example thereof. In this example, the duration of each of a number of phonemes (consonants and vowels) is first obtained and then the duration of a syllable, i.e., a synthesis unit, is obtained by summing up all the durations of the phonemes.

TABLE 1-continued

Flow Chart and Example of Sentence Analysis Function

Flow	Example		
Allocate duration to each phoneme according to duration specific to the phoneme and speaking speed (specified by user).	W A T A SH I	90 ms 100 ms 110 ms 100 ms 120 ms 90 ms	.
Control duration of each phoneme considering extension and reduction due to the number of syllables in a breathing interval, extension and reduction of the first and last syllables in a breathing interval, and influence of adjacent syllables.	W A T A SH I	85 ms 87 ms 110 ms 83 ms 120 ms 81 ms	.
Calculate duration of each synthesis unit	W A T A SH I	85 ms 87 ms 110 ms 83 ms 120 ms 81 ms	85 ms 87 ms } → WA 172 ms 110 ms 83 ms } → TA 193 ms 120 ms 81 ms } → SHI 201 ms

Thus, with the duration of each of the synthesis units in the text obtained by the sentence analysis function, the period length and synthesis parameters of each of the frames are next to be interpolated for each of the synthesis units (Step 16), as illustrated in detail in FIG. 6. Namely, an interpolation variable x is first obtained. Since $t = t_0 + x (t_1 - t_0)$, the following expression is obtained (Step 161).

$$x = \frac{t - t_0}{t_1 - t_0}$$

50 From the above expression, it can be seen to what extent each of the synthesis units is near to the origin for interpolation. Next, the period length T_i and the synthesis parameter r_i of each of the frames in each of the synthesis units are obtained from the following expressions, respectively, with reference to the parameter file (Step 162 and 163).

$$T_i = T_0 - x \Delta T_i$$

$$60 \quad r_i = p_i - x \Delta p_i$$

Thereafter, a speech is synthesized based on the period length T_i and the synthesis parameters r_i (Step 17 in FIG. 2). The speech synthesis function is represented schematically in FIG. 8. Namely, a speech model is considered to include a sound source 18 and a filter 19. Signals indicating whether a sound is voiced (pulse train) or unvoiced (white noise) (indicated with U and

V, respectively) are supplied as sound source control data, and line spectrum pair parameters, etc., are supplied as filter control data.

As a result of the above processing, speeches of a text, for example "私は、言葉を..." shown in Table 1, 5 are synthesized and spoken through the speaker 9.

The following Tables 2 through 5 show, as an example, the processing of the syllable "WA" extending over a duration of 172 ms. Namely, Table 2 shows the analysis of the speech of the syllable "WA" having the analysis frame period of 10 ms and extending over the dura-

Table 3 shows the analysis of the speech of the syllable "WA" having the same frame period and extending over the duration of 150 ms (a speech spoken at a higher speed). Table 4 shows the correspondence between these speeches by DP matching. A portion of the parameter file for the syllable "WA" prepared according to Tables 2 through 4 is shown in Table 5. (The line spectrum parameters). Table 5 shows also the period length and synthesis parameters (the first parameters) of each of the frames in the speech of the syllable "WA" extending over the duration of 172 ms.

In Table 5, p_i, Δp_i, q_j, and r_i are shown only as to the first parameters.

While the present embodiment has been explained above with respect to an example employing the system illustrated in FIG. 1, it is of course possible to realize the present invention with a small system by employing a signal processing board 20 as illustrated in FIG. 9. In the example illustrated in FIG. 9, a workstation 1A performs the functions of editing a sentence, analyzing the sentence, calculating variations, interpolation, etc. In FIG. 9, the portions having the functions equivalent to those illustrated in FIG. 1 are illustrated with the same reference numbers. The detailed explanation of this example is omitted here.

Next, two modifications of the above-stated embodiment will be explained.

In one of the modifications, training of the parameter file is discussed. It is noted that errors occur when such training is not performed. FIG. 10 illustrates the relations between synthesis parameters and durations. In FIG. 10, to generate the synthesis parameters r_i from the parameters p_i for the speech spoken at the lower speed and the parameters q_j for the speech spoken at the higher speed, interpolation is performed by using a line OA₁, as shown with a broken line (a). Similarly, to generate synthesis parameters r_{i'} from (i) parameters s_k for another speech spoken at another higher speed (extending over a duration t₂) and the (ii) parameters p_i, interpolation is performed by using a line OA₂, as shown with a broken line (b). Apparently, the synthesis parameters r_i and r_{i'} are different from each other. This is due to the errors, etc., caused in matching by the DP matching.

In this modification, the synthesis parameters r_i are now generated by using a line OA' which is obtained by averaging the lines OA₁ and OA₂, so that there would be a high probability that the errors of the lines OA₁ and OA₂ would be offset by each other, (e.g. by adding line OA₁ to line OA₂) as seen from FIG. 10. According to FIG. 10, it is observed that t₁ is replaced by t_{1'}, q_j is replaced by q_{j'}, and a new r_i is set along line OA' at time t. Although the training is performed once in the example shown in FIG. 10, it is obvious that additional train-

ing would result in smaller errors, as in this modification.

FIG. 11 illustrates the procedures in this modification, with portions similar to those in FIG. 2 illustrated with similar numbers. Similar steps are not explained here in detail.

In FIG. 11, the parameter file is updated in Step 21, and the necessity of training is judged in Step 22 so that the Steps 11, 12, and 21 would be repeated when needed.

Although, in Step 21, ΔT_i and Δp_i are obtained according to the following expressions,

$$\Delta T_i = \Delta T_i + \left(\frac{n_j - 1}{n_j} \right) T_0$$

$$\Delta p_i = \Delta p_i + (p_i - q_j)$$

it is obvious that a processing similar to the Steps in FIG. 2 is performed since ΔT_i = 0 and Δp_i = 0 in the initial stage. When the values after a training corresponding to those before a training

$$(t_1 - t_0), (p_i - q_j), \text{ and } \left(\frac{n_j - 1}{n_j} \right)$$

are denoted, respectively, with apostrophes attached thereto, as

$$(t_1 - t_0)', (p_i - q_j)', \text{ and } \left(\frac{n_j - 1}{n_j} \right)',$$

the following expressions are obtained (See FIG. 10).

$$(t_1 - t_0)' = t_1' - t_0 = (t_1 - t_0) + (t_2 - t_0)$$

$$(p_i - q_j)' = p_i - q_j' = (p_i - q_j) + (p_i - s_k)$$

-continued

$$\left(\frac{n_j - 1}{n_j} \right)' = \frac{n_j - 1}{n_j} + \frac{n_k - 1}{n_k}$$

Accordingly, when the values after the training correspond to those before the training, Δp_i and ΔT_i , are denoted as $\Delta p'_i$ and $\Delta T'_i$, respectively, the following expressions are obtained.

$$\Delta p'_i = (p_i - q_j)' = \Delta p_i + (p_i - s_k)$$

$$\Delta T'_i = T_0 \left(\frac{n_j - 1}{n_j} \right) = \Delta T_i + T_0 \left(\frac{n_k - 1}{n_k} \right)$$

Further, when an interpolation variable after the training is denoted as x' , the following expressions are obtained.

$$x' = \frac{t - t_0}{(t_1 - t_0)'} = \frac{t - t_0}{(t_1 - t_0) + (t_2 - t_0)}$$

or

$$\frac{1'}{x'} = \frac{(t_1 - t_0) + (t_2 - t_0)}{t - t_0} = \frac{1}{x} + \frac{t_2 - t_0}{t - t_0}$$

In Step 21 in FIG. 11, apostrophe's are omitted, and k and s are replaced with j and q , respectively.

With regard to the othe modification, it is noted that, in the above-stated basic embodiment, the parameters obtained by analyzing the speech spoken at the lower speed are used as the origin for interpolation. Therefore, a speech to be synthesized at a speaking speed near that of the speech spoken at the lower speed would be of high quality since parameters near the origin.

For interpolation can be employed. On the other hand, the higher the speaking speed of a speech to be synthesized is, the more the quality would be deteriorated. For improving the quality of a synthesized speech parameters obtained by analyzing a speech spoken at such a speed as is used most frequently (this speed is hereinafter referred to as "a standard speed") are used as the origin for interpolation. Accordingly, when a speech is at a speaking speed higher than the standard speed, is to be synthesized, the abovestated embodiment itself may be applied thereto by employing the parameters obtained by analyzing the speech spoken at the standard speed as the origin for interpolation.

On the other hand, in synthesizing a speech at a speaking speed lower than the standard speed, a plurality of frames in the speech spoken at the lower speed may correspond to one frame in the speech spoken at the standard speed, as illustrated in FIG. 12, and in such a case, the average of the parameters of the plurality of frames is employed as the end for interpolation on the side of the speech spoken at the lower speed.

More specifically, when the duration of the speech spoken at the standard speed is denoted as t_0 ($t_0 = MT_0$) and the duration of the speech spoken at the lower speed is denoted as t_1 ($t_1 = NT_0$, $N > M$), the parameters of each of the M frames in the speech to be synthesized, extending over the duration t ($t_0 \leq t \leq t_1$), is obtained. (See FIG. 12.) When $t = t_0 + x(t_1 - t_0)$, the duration T_i and the synthesis parameters r_i of the "i"th frame are respectively expressed as

$$T_i = T_0 + xT_0(n_i - 1)$$

$$5 \quad r_i = p_i - x \left(p_i - \frac{1}{n_i} \sum_{j \in J_i} q_j \right)$$

where p_i denotes the parameters of the "i"th frame in the speech spoken at the standard speed, q_j denotes the parameters of the "j"th frame in the speech spoken at the lower speed, J_i denotes a set of the frames in the speech spoken at the lower speed corresponding to the "i"th frame in the speech spoken at the standard speed, and n_i denotes the number of elements of J_i .

10 Thus, by determining uniquely the parameters of each of the frames in the speech spoken at the lower speed, corresponding to each of the frames in the speech spoken at the standard speed, in accordance with the expression.

20

$$\frac{1}{n_i} \sum_{j \in J_i} q_j,$$

25 it is possible to determine the parameters for a speech to be synthesized at a lower speed than the standard speed by interpolation. Of course, it is also possible to perform the trainings of the parameters in this case.

30 As explained above, the present invention obtains a synthesized speech extending over a variable duration by interpolating the synthesis parameters obtained by analyzing speeches spoken at different speeds. The processing of the interpolation is convenient and can add the characteristics of the original synthesis parameters. Therefore, according to the present invention, it is possible to obtain a synthesized speech extending over a variable duration conveniently without deteriorating the phonetic characteristics. Further, since training is 35 possible, the quality of the synthesized speech can be further improved as required. The present invention can be applied to any language. The parameter file may be provided as a package.

40 Having thus described my invention, what I claim as new, and desire to secure by Letters Patent is:

- 45 1. A speech synthesis process comprising the steps of:
  - (a) generating, for each of synthesis units for speech synthesis, a plurality of first data portions, each having a fixed period length, from a first speech data representing each of said synthesis units;
  - (b) generating, for each of said synthesis units, the same number of second data portions as that of said first data portions, each of said second data portions corresponding acoustically to each of said first data portions, from at least one second speech data representing each of said synthesis units, said second speech data extending over a duration different from that of said first speech data;
  - (c) determining a synthesis unit to be synthesized;
  - (d) determining a target duration of said determined synthesis unit;
  - (e) determining a period length of each of a series of synthesis frames, said series of synthesis frames extending over said determined target duration of said determined synthesis unit and comprising the same number of frames as that of said first data portions, by interpolation based on said determined target duration of said determined synthesis unit,

with reference to each of period lengths of said first and second data portions for said determined synthesis unit, each of said first and second data portions corresponding to each of said synthesis frames;

- 5
(f) determining synthesis parameters to each of said synthesis frames, by interpolation based on said determined target duration of said determined synthesis unit, with reference to each of synthesis parameters of said first and second data portions for 10 said determined synthesis unit, each of said first and second data portions corresponding to each of said synthesis frames; and
(g) synthesizing a speech based on said determined period length and synthesis parameters of each of 15 said synthesis frames.

2. A speech synthesis process as described in claim 1, wherein:

- one second speech data is employed in said Step (b);
and
20
said Step (b) comprises the sub-steps of;
generating a plurality of third data portions, each having a fixed period length, from said second speech data;
matching said third data portions with said first data 25 portions based on their acoustic characteristics; and
dividing said second speech data into said second data portions based on said matching.

3. A speech synthesis process as described in claim 1, 30 wherein:

- more than one second speech data is employed in said Step (b); and
said Step (b) comprises the sub-steps of;
generating a plurality of third data portions, each 35 having a fixed period length, from each of said more than one second speech data;
matching said third data portions with said first data portions, for each of said more than one second speech data, based on their acoustic characteristics; 40
dividing one of said more than one second speech data into said second data portions based on said matching for one of said more than one second speech data; and
correcting said period length and synthesis parameters of each of said second data portions based on 45 said matching for the other or each of the others of said more than one second speech data.

4. A speech synthesis process as described in claim 1, 50 wherein;

- said fixed period length is a period length of an analysis frame.

5. A speech synthesis process as described in claim 2, wherein;

- said sub-step of matching is performed based on a 55 dynamic programming.

6. A speech synthesis process as described in claim 1, wherein;

- said duration of said first speech data is a standard speaking period according to said determined synthesis unit.

7. A speech synthesis system comprising:

- (a) storage means for storing a first data and a second data generated for each of synthesis units for speech synthesis parameters of each of a plurality of first data portions, each having a fixed period length, generated from a first speech data representing each of said synthesis units, and said second

data representing a period length and synthesis parameters of each of the same number of second data portions as that of said first data portions, each of said second data portions corresponding acoustically to each of said first data portions, generated from at least one second speech data representing each of said synthesis units, said second speech data extending over a duration different from that of said first speech data;

- (b) means for determining a synthesis unit to be synthesized;
(c) means for determining a target duration of said determined synthesis unit;
(d) means for determining a period length of each of a series of synthesis frames, said series of synthesis frames extending over said determined target duration of said determined synthesis unit and comprising the same number of frames as that of said first data portions, by interpolation based on said determined target duration of said determined synthesis unit, with reference to said first and second data stored in said storage means;
(e) means for determining synthesis parameters of each of said synthesis frames, by interpolation based on said determined target duration of said determined synthesis unit, with reference to said first and second data stored in said storage means; and
(f) means for synthesizing a speech based on said determined period length and synthesis parameters of each of said synthesis frames.

8. In speech synthesis wherein words are characterized as sequences of synthesis units, a method of synthesizing speech for a synthesis unit based on a plurality of utterances thereof, the method comprising the steps of:

- generating a first series of M frames of analysis data, one frame every T_0 period, in response to a low-speed utterance of the synthesis unit, each frame having a parameter value corresponding thereto; generating a second series of N frames of analysis data, one frame every T_0 period, in response to a high-speed utterance of the synthesis unit, each frame having a parameter value corresponding thereto;

segmenting some of the T_0 periods of the second series into divided data portions, the undivided T_0 periods and the data portions forming M data intervals for the high-speed utterance, the T_0 periods of the first series matching, one-by-one, the data intervals of the second series;

interpolating the time length of each i th interval ($1 \leq i \leq M$) of synthesized data for the synthesis unit to be bound by (i) T_0 and (ii) the time length of the i th data interval of the high-speed utterance; and

interpolating the parameter value of each i th frame of synthesized data for the synthesis unit to be bound by (i) the parameter value of the i th frame of the first series and (ii) the parameter value of the i th data interval of the second series.

9. The method of claim 8 wherein the time interval interpolation includes the step of:

calculating an interpolation variable x which indicates conformity between the time lengths corresponding to the synthesized data and time lengths corresponding to either the low-speed utterance or the high-speed utterance.

10. The method of claim 9 comprising the further step of:

calculating the time length of each frame T_i of the synthesized data as:

$$T_i = T_0 - x \Delta T_i$$

where ΔT_i is the difference in length between the period length of the i th frame in the first series and the time length for the i th time interval of the high-speed utterance.

11. The method of claim 10 wherein the parameter interpolating step includes the step of: calculating a parameter value r_i for the i th time interval of the synthesized data as:

$$= -\Delta r_i = p_i - x \Delta p_i$$

where p_i is the parameter value of the i th frame in the first series and Δp_i is the difference in value between (i) p_i and (ii) the parameter value for the i th time interval corresponding to the high-speed utterance.

12. In speech synthesis wherein words are characterized as sequences of synthesis units, a method of synthesizing speech for a synthesis unit based on a plurality of utterances thereof at differing speeds, the method comprising the steps of:

generating, for each utterance of the synthesis unit, a series of frames of analysis data, the frames being generated one frame every T_0 period, each frame in each series having a parameter value associated therewith;

where one series results in M frames of data, partitioning each other series of frames to provide M time intervals each of which corresponds to one of the frames of said one series;

synthesizing speech data for the synthesis unit, the synthesized speech data corresponding to a sequence of time intervals wherein each time interval has an associated parameter value, said synthesizing step including the steps of:

representing the synthesized data as a sequence of M time intervals, interpolating each i th time interval (where $1 > i > M$) for the synthesized data from the respective i th intervals corresponding to the utterance; and

interpolating the parameter value at each i th time interval of the synthesized data from the parameter values for the respective i th intervals corresponding to the utterances.

13. A speech synthesis system comprising: means for generating first speech data representing a unit of synthesized speech extending over a first time duration, said first time duration being divided into a series of first frame periods having lengths, said first speech data comprising a plurality of first data portions, each first data portion representing the length of a first frame period and a first speech synthesis parameter of the unit of synthesized speech corresponding to the first frame period;

means for generating second speech data representing the unit of synthesized speech extending over a second time duration different from the first time duration, said second time duration being divided into a series of second frame periods having lengths, each second frame period corresponding to a first frame period, said second speech data comprising a plurality of second data portions, each second data portion representing the length of a second frame period and a second speech synthesis parameter of the unit of synthesized speech corresponding to the second frame period;

5

sis parameter of the unit of synthesized speech corresponding to the second frame period; means for generating third speech data representing the unit of synthesized speech extending over a third time duration different from the first and second time durations, said third time duration being divided into a series of third frame periods having lengths, each third frame period corresponding to a first and a second frame period, said third speech data comprising a plurality of third data portions, each third data portion representing the length of a third frame period and a third speech synthesis parameter of the unit of synthesized speech corresponding to the third frame period, said means for generating the third speech data comprising:

means for calculating the length of each third frame period by interpolating between the lengths of the corresponding first and second frame periods; and

means for calculating each third speech synthesis parameter by interpolating between the first and second speech synthesis parameters of the corresponding first and second frame periods; and means for synthesizing speech from the third speech data.

15

14. A speech synthesis system as claimed in claim 13, characterized in that the first time periods have equal lengths.

15. A speech synthesis system as claimed in claim 14, characterized in that the third time duration is between the first and second time durations.

16. A speech synthesis system as claimed in claim 15, characterized in that the number of first frame periods is equal to the number of second frame periods.

17. A speech synthesis system as claimed in claim 15, characterized in that:

the number of first frame periods is not equal to the number of second frame periods; and means are provided for determining the correspondence between first frame periods and second frame periods, said means determining correspondence by dynamic programming.

18. A speech synthesis method comprising the steps of:

generating first speech data representing a unit of synthesized speech extending over a first time duration, said first time duration being divided into a series of first frame periods having lengths, said first speech data comprising a plurality of first data portions, each first data portion representing the length of a first frame period and a first speech synthesis parameter of the unit of synthesized speech corresponding to the first frame period;

generating second speech data representing the unit of synthesized speech extending over a second time duration different from the first time duration, said second time duration being divided into a series of second frame periods having lengths, each second frame period corresponding to a first frame period, said second speech data comprising a plurality of second data portions, each second data portion representing the length of a second frame period and a second speech synthesis parameter of the unit of synthesized speech corresponding to the second frame period;

generating third speech data representing the unit of synthesized speech extending over a third time

30

duration different from the first and second time durations, said third time duration being divided into a series of third frame period having lengths, each third frame period corresponding to a first and a second frame period, said third period corresponding to a first and second third data portions, each third data portion representing the length of a third frame period and a third speech synthesis parameter of the unit of synthesized speech corresponding to the third frame period, said step of 10 generating the third speech data comprising: calculating the length of each third frame period by interpolating between the lengths of the corresponding first and second frame periods; and calculating each third speech synthesis parameter 15 by interpolating between the first and second speech synthesis parameters of the corresponding first and second frame periods; and

5

synthesizing speech from the third speech data. 19. A speech synthesis method as claimed in claim 18, characterized in that the first time periods have equal lengths. 20. A speech synthesis method as claimed in claim 19, characterized in that the third time duration is between the first and second time durations. 21. A speech synthesis method as claimed in claim 20, characterized in that the number of first frame periods is equal to the number of second frame periods. 22. A speech synthesis method as claimed in claim 20, characterized in that: the number of first frame periods is not equal to the number of second frame periods; and further comprising the step of determining the correspondence between first frame periods and second frame periods by dynamic programming.
